LOOSE LEAF BINDER

Filed Dec. 6, 1930

UNITED STATES PATENT OFFICE

JAMES C. DAWSON, OF WEBSTER GROVES, MISSOURI, ASSIGNOR TO ELMA N. DAWSON,
OF WEBSTER GROVES, MISSOURI

LOOSE LEAF BINDER

Application filed December 6, 1930. Serial No. 500,448.

This invention relates to loose leaf binders, and particularly to binders in which wire elements form the toggle system. Forming an intermediate prong upon such a toggle member or arch frame of loose leaf binders either 5 has produced a clumsy, unsymmetrical device, or the expense of the operation has proved an intolerable burden.

By a custom of the trade, loose leaf binder merchandise falls into three groups, the 10 cheapest being simply cardboard cover sheets having eyelets therein with loose locking rings passed through the eyelets. The next grade consists of binders incorporating wire arch frames, while the higher grades of merchandise are supplied with flat toggle plates which support the paper holding arches.

Because of the low price at which wire arch frame binders must be sold, all operations of manufacture must be expeditious and exceedingly cheap. As a consequence wire arch frame binders have been available commercially with only two paper-holding arches, which have been formed integrally upon the 20 ends of the toggles, although in such binders there is the same need for three or more prongs as exists in binders of the more expensive types.

The principal object of this invention is to 30 provide binders of the wire arch frame type with as many paper holding rings or arches as may be desired.

In my United States Patent No. 1,675,299, June 26, 1928, I disclosed a method for the 35 manufacture of such loose locking rings in an automatic, convenient and inexpensive manner. In the present instance I attach these rings to the wire arch frames to form a three prong loose leaf binder.

40 In the drawings:

Fig. 1 illustrates such a binder showing a portion only of the book cover;

Fig. 2 is a bottom plan view of the binder shown in Fig. 1;

45 Fig. 3 is a vertical section through the binder on the line 3—3 of Fig. 2;

Fig. 4 is a vertical transverse section through the binder, on the line 4—4 of Fig. 2;

50 Fig. 5 illustrates in bottom plan view a common form of wire arch spring binder

in which the cover plate is crimped about the arch frames;

Fig. 6 is a vertical transverse view on the line 6—6 of Fig. 5;

Fig. 7 is a vertical transverse view on the 55 line 7—7 of Fig. 5, illustrating also an alternative type of ring; and

Fig. 8 illustrates a modification of the ring.

As indicated in the figures, wire arch frame binders are composed of two bent 60 wires 11, 11, of a peculiar configuration. Each end 12 of each wire is formed into one-half of a paper-holding ring or "arch" and cooperates with the similar wire oppositely placed. The wires 11 are bowed to put a wind 65 into the wire, and these bowed portions abut each other and coact to cause the arches to snap into and out of engagement when the wires are rotated. The wire arch frames 11 may be pivoted upon the outer margins of the clearance holes 13 in the cover plate 14, as shown in Fig. 3, or they may be pivoted along their length in the hooked margin 15 of the cover plate 16 (Fig. 5).

The cover plate 14 is provided with clearance holes 17, 17, for an intermediate ring 18, preferably made in accordance with Patent No. 1,675,299, and is welded to the wire arch frames 11, 11, at the points 19, 19.

Fig. 7 illustrates a form of intermediate 80 ring which is composed of two similar prongs 21, 22, which butt together at the point 23 and roll against each other along their curved inner ends 24.

In the modification shown in Fig. 8, the 85 ring is made up of two dissimilar prongs 25 and 26. The prong 25 is provided with a notch 27, while the prong 26 bears a tongue 28 which engages in the notch 27.

The form in Fig. 7 is open to the objection 90 that pressure upon either one of the prongs may cause them to be displaced relative to one another, while the form shown in Fig. 8 requires that "right" and "left" prongs for the ring be manufactured and properly assembled.

When the intermediate ring is to be welded 95 to the type of binder shown in Fig. 5, it is necessary to cut away the hooked margins 15, 100

15 as at 29 and 31 to give clearance to the welding tool.

While for manufacturing reasons I prefer to use the rings shown and have selected such 5 rings to illustrate the present embodiment of my invention, it is understood that this is not the essence of the invention and that intermediately located paper holding prongs attached to wire arch frames come fairly 10 within its scope.

What I claim, therefore, is:

1. A loose leaf binder comprising a cover plate, a pair of oppositely disposed wire arch frames pivoted on the cover plate, and a two- 15 part hinged ring forming a paper-holding arch extending through the cover plate and having its parts affixed to the longitudinal portions of the two frames respectively.

2. A loose leaf binder having a cover plate, 20 a pair of articulated wire frames retained by the cover plate and pivoted thereon to form a dead center mechanism, and a paper-holding prong intermediately positioned upon each arch frame and each arranged to 25 mate with the corresponding prong upon the opposite frame, said prongs having their inner ends in engagement.

3. In a loose leaf binder, a pair of wire arch toggle members bearing mating paper- 30 holding prongs at their ends, and a pair of intermediately located paper-holding prongs secured to said toggle members and having lower end portions of said intermediately located prongs articulated to form a toggle 35 joint.

4. A loose leaf binder comprising a cover plate, a pair of oppositely disposed wire frames pivoted to the cover plate each bearing a paper-holding prong adjacent its ends, 40 a paper holding prong attached to one frame at an intermediate position projecting through the plate, and means to secure the continuous engagement of that end of the prong lying beneath the plate with a similar 45 oppositely disposed prong attached to the other frame.

5. A loose leaf binder comprising a cover plate, a pair of wire frames having terminal paper-holding prongs pivoted in said plate, 50 a pair of intermediate paper-holding prongs comprising a hinged ring attached to each frame and having its hinge below the plate and between the wire frames.

In testimony whereof I affix my signature.

JAMES C. DAWSON.
